UNITED STATES PATENT OFFICE.

KARL OSKAR LEON, OF LONDON, ENGLAND.

MANUFACTURE OF ROLLERS FOR ROLLER BEARINGS.

Application filed April 21, 1923. Serial No. 639,710.

To all whom it may concern:

Be it known that I, KARL OSKAR LEON, a subject of the King of Sweden, and residing at 115 Great Portland Street, London, W. 1, England, have invented certain new and useful Improvements in and Relating to the Manufacture of Rollers for Roller Bearings, of which the following is a specification.

10 This invention relates to the manufacture of rollers for roller bearings and more particularly to that kind known as disc rollers.

One of the objects of the present invention is to provide an improved method of 15 grinding the rollers of roller bearings, according to which each roller is tilted to and fro between predetermined limits at the same time as it is rotated on edge in operative contact with a rotating grinding disc, 20 so as to grind the rollers to a transversely curved periphery.

Another object of the invention is to construct a machine for carrying out the above method of grinding, and in which the rollers 25 can be ground to the exact diameter required, and to the exact periphery required.

The invention will now be described with reference to the accompanying drawings, in which:—

30 Figure 1 is a sectional elevation of one form of machine constructed according to the present invention.

Figure 2 is a similar elevation of the upper part of a modified machine and drawn 35 to a larger scale.

Figure 3 is an irregular inverted horizontal section on the line 3—3 of Figure 2,

Figure 4 is an enlarged detail of Figure 1, and

Figure 5 is a diagram hereinafter referred to.

In carrying the invention into effect, the machine comprises a fixed main frame *a* supported by a wall or standard. The lower half of the machine consists of a horizontally arranged circular grindstone *b* protected by a guard *c*, the grindstone being carried on a vertical spindle *d* which is midway of its length, slidably supported by a bracket *e* fixed to the frame *a*, whilst its ends are carried and supported by brackets *f* and *g* respectively. These brackets are adapted to be simultaneously moved in suitable guiding slots relatively to the fixed frame *a* by means of a bracket *f* through which is threaded an adjusting screw *h*

supported at each end by brackets *j* forming a part of the main frame. The upper end of the adjusting screw *h*, which is immovable lengthwise, is adapted to be rotated by a bevelled pinion *k* which is in engagement with a corresponding bevelled pinion *l*, which is adapted to be rotated by means of a handwheel *m*. To permit the bracket *f* to move relatively to the main frame the latter is slotted at *a* and the bracket *f* passes through the slot. When the handwheel *m* is rotated the bevelled pinions *l*, *k* transmit this movement to the adjusting screw *h*, whereby the bracket *f* and therefore the brackets *f* and *g* are bodily raised or lowered relatively to the central fixed bracket *e* thereby properly adjusting the height of the grinding disc *b* as desired.

The bracket *e* is formed by two arms which afford bearings for a sleeve *e* to which there is keyed the driving pulley *n* which is arranged in between the two arms of the bracket *e* and the sleeve *e* is provided with a long keyway to engage with a key *e*, as shown, by which the driving pulley *n* imparts movement to the spindle *d* by which the grind-stone is always driven whether it is to be adjusted or otherwise.

The lower end of the spindle is carried in a suitable footstep bearing *o* as illustrated, that is contained by the bracket *g*.

The upper half of the machine comprises a roller cage *p* which is arranged in parallel relation with and above the upper surface of the grinding disc *b*, and such cage is suspended from a spider frame *q* which is centrally and fixedly suspended from a stem *r* which is vertically arranged within and fixedly supported by a tubular bracket *s* which forms a part of a frame *t* which is held in suitable fixed relation with the main frame *a*. For the purpose of accurately adjusting the frame *t* suitable bearing slots may be provided, which are not shown, for attaching it to the main frame *a*.

There is arranged within the stem *r* a spindle *u* which is extended through the centre of the spider frame *q*, and is fitted towards its lower end with an enlarged shoulder *V*, and beneath the shoulder is rigidly connected to a pin *w*, which as seen in Figure 1, is eccentric to the spindle *u*. Secured upon the enlarged shoulder *V* of the spindle is a spur wheel *x* which is in engagement with a toothed pinion *y* mounted

upon the lower end of the driving spindle z , which is vertically arranged and supported by a suitable bearing formed in the frame t . The upper end of the spindle z 5 carries a pulley 9 which is adapted to be driven by means of a band or otherwise from any suitable source of power.

Arranged around or upon the eccentric pin W is an eccentrically formed sleeve 10 10 which is contained within an upstanding central boss 11 formed upon a horizontally arranged pressure disc 12 which is in parallel relation with and arranged above the cage ring p , and a number of grinding seats 15 13 are spaced around the disc 12 , the seats facing downwards and being constructed as hereinafter described. The eccentrically formed sleeve 10 is flanged at its lower end 20 so as to be properly fitted within and held against the lower side of the disc 12 , it being maintained in position by means of a nut 15 which is screwed or otherwise attached to the lower end of the eccentric pin W . By this means, the horizontal driving 25 disc 12 , the spindle u and the spur-wheel x are securely clamped together.

Between the enlarged shoulder V and the underside of the centre of the spider frame q a spring 16 is arranged, as clearly shown 30 in Figure 1, and in order that the spur wheel x , the eccentric pin W , boss 11 , and the disc 12 with the grinding seats attached thereto may be all bodily raised against the force of the compression spring 16 , the spindle u 35 is provided about midway of its length with a cylindrical rack 17 which is keyed to the spindle u and is accommodated within a space formed within the stem r . In order that the cylindrical rack may be raised or 40 lowered, the teeth thereon are in engagement with a pinion 18 supported upon a spindle 19 and adapted to be rotated by means of a rack 20 which is adapted to be 45 raised or lowered by means of a handwheel 21 . The centre spindle of the handwheel 21 is screw-threaded as shown, and imparts an elastic pressure due to the spring 22 upon the end of the rack 20 , so that when the handwheel 21 is operated in one direction or 50 the other, the spindle u will be raised or lowered as the case may be and thereby withdraw the horizontal disc from the position shown, or lower it for the purpose hereinafter described, the gearing between 55 the spur wheel x and the pinion y being always maintained.

The withdrawing movement of the horizontal disc 12 may be limited by a fixed arm 23 which extends from the fixed frame t to within the spider frame q , as shown.

The cage ring p arranged immediately above the grinding disc b is provided with a number of slots 24 near its outer edge, each slot being adapted to receive a disc roller which is to be ground. The slots 24 are

spaced as close as possible together all round the cage ring so that as many disc rollers as possible may be treated at one time. The form of each slot is such as will permit the roller to oscillate from side to side and it is preferred to fit each slot at its respective end with facing plates or discs 25 , the lower plate having an opening which practically fits the width of the roller, whilst the upper disc 25 has an opening which corresponds with the larger end of the tapered slot formed in the cage ring, and which will allow for the tilting movement of the disc roller. The seats formed in the horizontal disc 12 are of special form such as clearly 80 illustrated in a detail view Figure 4, and are constructed as follows:—

The edge of the horizontal disc 12 at its lower side is provided with a thickened boss 26 which forms a casing to contain a replaceable annular block 27 , which is maintained in position therein by a screw stud 28 . On each side of the block 27 there is fitted a spring tongue 29 , whilst the under-surface of the block itself has a convex face as shown clearly in Figure 4. When the machine is in running order the rotation of the spur wheel x causes a rotation of the disc 12 mounted upon the eccentric sleeve 10 and the eccentric pin W , thereby causing the disc 12 to have not only a rotational movement of translation but also an oscillating movement, which causes the rollers which have to be ground to turn on their own axes as well as to tilt sidewise. The grinding of the rollers is caused by a difference of speed between the horizontal disc 12 and the grinding disc b and as each roller disc is tilted its periphery is more and more ground to a convex form as regulated by the degree of convexity previously given to the block 27 .

It is to be noted that as each roller disc tilts first to one side or to the other it will flex one of the spring tongues 29 to ensure that with the return movement of the disc 12 the disc roller shall again resume its upright position relatively to the grinding disc b .

In order that the degree of eccentric movement given to the horizontal disc 12 may be adjusted, the eccentric sleeve 10 may be moved so that its throw may either be brought into coincidence with the eccentric throw of the pin W , in which case the geometrical centre of the disc 12 becomes fixed, or the sleeve 10 may be so adjusted that this throw will be added to that of the pin W . To permit this adjustment being effected when the machine is being previously set, the grinding disc may be lowered sufficiently to enable the nut 15 to be slackened and to turn the eccentric sleeve to the degree desired, and in order that this amount of adjustment may be correctly indicated the

flange on the lower end of the eccentric sleeve carries an index 30 which is designed to register with a series of graduations 31, as is seen clearly in Figure 3. After the 5 adjustment is made the nut 15 is tightened and the machine is then ready to operate under the new adjustment.

The diagram shown in Figure 5 illustrates 10 clearly the arrangement of this adjustable eccentric, the black line 32 representing the throw due to the eccentric pin W and with the throw of the eccentric sleeve in coincidence therewith, but when the sleeve has been adjusted through 180° the total throw 15 imparted to the mechanism is indicated by the addition of the dotted length 33 and the black line 32.

For normal grinding the weight of the 20 parts, that is to say, the spur wheel π , the horizontal disc 12 and their associated members resting upon the disc rollers exert sufficient pressure. If any extra grinding pressure is temporarily required, the upper part of the stem r is fitted with a bracket 34 25 which serves as a fulcrum for a lever 35 adapted to be pressed down upon the upper end of the spindle u , so that should any further grinding pressure be required it may be supplied.

30 In the drawings it is to be noted that the centre axis of the spindle u is slightly out of alignment with that of the grinding disc. Such an arrangement of the two axes will ensure a slight traversing motion over the 35 grinding face to better distribute the grinding surface.

The second modification shown in Figure 2 is substantially the same as that already described, but the horizontal driving disc 12 is fitted with a pin 12^a engaging with a slot 12^b in the spider frame q so as to prevent rotation of the disc 12. It will however receive the oscillating movement described. In this figure instead of the handwheel 21 15 being horizontal it is vertically arranged and is mounted directly on the spindle 19 of the pinion 18. The seatings 13 are slightly modified. As shown in Figure 2 a series of openings 36 are bored through 20 the edge of the horizontal disc 12 with a projecting flange 37 at the lower end. This receives and supports a set of pressure discs 38 each having a centre pin 39 which is held in position by a screw cap 40, a spring 41 25 being arranged above the centre pin 39 and inside the cap 40. The lower face of the pressure disc 38 rests on the top of the corresponding disc roller. To decrease friction between the parts at the centre, ball bearings 42 are provided between the centre boss 11 30 and the eccentric sleeve 10.

By the foregoing constructions it is possible to grind disc rollers to the form desired with great accuracy and with speed.

35 The mechanical details may be varied with-

out departing from the general principles involved.

Such a machine is moreover adapted to form part of a system for producing rollers in mass, as the rollers after being ground 70 may be passed to a lapping machine, and finally led to a measuring machine where they may be graded, these two latter machines being constructed as described in the specifications of my U. S. Patent No. 75 1,465,555 and my U. S. application Ser. No. 632,730.

Having now described my invention, what I claim as new and desire to secure by Letters Patent is:—

1. A roller grinding machine comprising the combination of a grinding disc, a crown plate facing the disc and parallel thereto, said disc and plate being adapted to receive between them a series of rollers to 85 be ground arranged on edge, means for causing relative rotatory movement between the disc and plate, and means for imparting also a motion of translation to the crown plate in order to thereby cause the rollers to tilt.

2. A roller grinding machine comprising the combination of a grinding disc, a crown plate facing the disc and parallel thereto, said disc and plate being adapted to receive between them a series of rollers to be ground arranged on edge, said crown plate having its axis of rotation permanently out of alignment with that of the grinding disc, adjustable means whereby the central geometrical axis of the crown plate is adapted to be arranged at different distances from the said axis of rotation of the crown plate, and means for causing relative rotatory movement between the disc 100 and plate.

3. A roller grinding machine comprising the combination of a grinding disc, a crown plate facing the disc and parallel thereto, said disc and plate being adapted to receive between them a series of rollers to be ground arranged on edge, means for causing relative rotatory movement between the disc and plate, means for tilting the series of rollers from side to side, and regulating means to adjustably limit the amplitude of such oscillation.

4. A roller grinding machine comprising the combination of a rotary grinding disc, a rotary crown plate facing the disc and parallel thereto, said disc and plate being adapted to receive between them a series of rollers to be ground arranged on edge, an intermediate cage ring for maintaining the rollers in position, and means for imparting an eccentric translational movement of adjustable amplitude to the crown plate in order to tilt the rollers from side to side.

5. A roller grinding machine comprising

the combination of a rotary grinding disc, a crown plate facing the disc and parallel thereto, said disc and plate being adapted to receive between them a series of rollers 5 arranged on edge, a series of seats in the crown plate corresponding to the number of rollers and each engaging a roller, means for causing relative rotational movement between the disc and crown plate, means for imparting eccentric translational movement to the crown plate in order to tilt the rollers from side to side and impart thereto 10 a convex periphery, and means whereby the seats for the rollers control the degree of convexity imparted to the periphery of each roller.

6. A roller grinding machine comprising the combination of a rotary grinding disc, a rotary crown plate facing the disc and 20 parallel thereto, a replaceable annular block on said plate, spring tongues on said plate at each side of the annular block, said grinding disc and said annular block being adapted to receive between them a series of 25 rollers to be ground arranged on edge and with their sides in contact with the said spring tongues, a stationary cage ring intermediate the plate and the disc for maintaining the rollers in position, and means 30 for imparting eccentric translational movement to the crown plate in order to tilt the rollers from side to side and impart thereto a convex periphery.

7. A roller grinding machine comprising 35 the combination of a rotary grinding disc, a rotary spindle, an eccentric pin on said spindle, an adjustable eccentric sleeve upon said pin, and a crown plate engaging upon said eccentric sleeve and arranged so as 40 to face said driving disc and be parallel thereto, said grinding disc and crown plate being adapted to receive between, and in

contact with them, a series of rollers to be ground arranged on edge.

8. A roller grinding machine as claimed 45 in claim 5, in which spring means are provided for elastically mounting the seats for the rollers within the crown plate.

9. A roller grinding machine comprising the combination of a rotary grinding disc, 50 a rotary spindle, a crown plate mounted upon said spindle, so that its geometrical axis is eccentric with regard to the axis of the spindle, said crown plate being arranged so as to face said driving disc and be parallel 55 thereto, said grinding disc and crown plate being adapted to receive between them a series of rollers arranged on edge, an intermediate cage ring for maintaining the rollers in position, and means for applying 60 pressure upon said rotary spindle so as to increase the pressure between the grinding disc and the rollers.

10. A roller grinding machine as claimed 65 in claim 3, in which there is provided intermediate the grinding disc and the crown plate a cage ring with orifices whose sides slope upwardly and outwardly for the purpose of engaging the rollers.

11. A roller grinding machine as claimed 70 in claim 9, in which manually operable means are provided for applying pressure upon the rotary spindle to increase the pressure between the grinding disc and the rollers.

12. A roller grinding machine as claimed 75 in claim 4, in which the crown plate, whilst being free to impart a tilting movement to the rollers, is prevented from making any substantial movement about its own axis. 80

In testimony whereof I have signed my name to this specification.

KARL OSKAR LEON.
